UNITED STATES PATENT OFFICE

2,215,221

BUCKLE FOR FOOTWEAR

Abraham I. Levine, Brooklyn, N. Y.

Application April 15, 1940, Serial No. 329,740

1 Claim. (Cl. 24—70)

This invention relates to buckled footwear. It is particularly directed to a shoe or boot provided with highly improved buckles to replace the laces on shoes.

5 An object of this invention is to provide a shoe of the character described having improved buckles for buckling the shoe, and which is so constructed that when the buckles are opened, there is no bridge between the adjacent edges at the front of the shoe, so that the foot may be readily set right into the shoe without interference by the buckles, the buckles being so constructed that they may be locked within a few seconds and opened up easily and rapidly.

10 15 A further object of this invention is to provide a shoe provided with a plurality of buckles which may be selectively tightened to various degrees, so that one part of the shoe may be tightened more than another part to accommodate the wearer, said buckles being independent of one another.

20 Yet a further object of this invention is to provide a shoe having strong, rugged and durable buckles of the character described, which may be readily manipulated and easily adjusted, and which shall be relatively inexpensive to manufacture, and practical and efficient to a high degree.

25 30 Other objects of this invention will in part be obvious and in part hereinafter pointed out.

The invention accordingly consists in the features of construction, combinations of elements, and arrangement of parts which will be exemplified in the construction hereinafter described, and 35 of which the scope of application will be indicated in the following claim.

In the accompanying drawing, in which is shown one of the various possible illustrative embodiments of this invention:

40 Fig. 1 is a perspective view of a shoe embodying the invention;

Fig. 2 is an enlarged, cross-sectional view taken on line 2—2 of Fig. 1;

Fig. 3 is an enlarged, front elevational view of 45 a portion of the shoe, and one of the buckles with parts broken away and in cross-section;

Fig. 4 is a cross-sectional view taken on line 4—4 of Fig. 2; and

Fig. 5 is a view similar to Fig. 4, but showing 50 the buckle opened up.

Referring now in detail to the drawing, 10 designates a shoe embodying the invention, slit at the front from the instep to its upper edge forming spaced adjacent edges 12 and 13. Inserted 55 within said edges 12 and 13 are aligned pairs of

metal strips 14 and 15. Said strips may be about two inches in length, there being as many pairs of metal strips as there are buckles 16 to be described in detail hereinafter.

The tongue 17 of the shoe covers the space between the adjacent edges 12 and 13. The strips 14 and 15 are attached to the shoe by means of rivets 18 and 19. The rear ends of the rivets may be covered by lining strips 18a and 19a.

Attached to each strip 14 is a buckle part 16a, 10 and attached to each strip 15, is a buckle part 16b. The buckle parts 16a and 16b cooperate to form the buckle 16.

The buckle part 16a comprises a channel shaped member 20 having a bottom wall 21 and parallel 15 side walls 22. The bottom wall 21 is fixed to the edge 12 of the shoe by the rivets 18 which pass through the metal strip 14. The front edges of the side walls are formed with aligned notches 23.

The notches 23 are inclined outwardly as shown 20 in Fig. 5 of the drawing. The buckle part 16b comprises a channel shaped member 24 having a bottom wall 25, attached to the edge 13 and to the metal strip 15 by said rivets 19. Extending from the bottom wall 25 are parallel side walls 26 25 carrying a transverse pivot pin 27. Pivoted to the pin 27 is a link 28 having parallel side walls 29 and an interconnecting top wall 30. The side walls 29 carry a transverse pivot pin 31 at the end of member 28 opposite the pin 27. Pivoted on 30 pin 31 is a lever 33 having a portion disposed between the walls 29 and carrying a transverse pin 34. The lever 33 is formed with a handle 35 at one end.

The distance between the parallel walls 22 of 35 member 20 is less than the distance between the walls 29 of link 28 and also less than the distance between the side walls of lever 33.

It will now be understood that to buckle up the shoe, each lever 33 is first swung in a counter-clockwise direction about pivot pin 31. The pin 34 is engaged in any desired pair of aligned notches 23. The lever is then rotated in a clockwise direction to tighten the buckle.

It will be noted that the metal strips 14 and 15 45 distribute the stress on the shoe. When the buckle is opened up, there is no bridge between edges 12 and 13, thus acting to facilitate placing the foot into the shoe. Each buckle may be tightened to a different desired degree. The buckles 50 may be readily locked or opened up. The improved buckles may be used for ice-skating shoe or ski-boots, and may be applied to any other type of footwear such as hiking boots, logger's boots and the like articles.

It will thus be seen that there is provided a device in which the several objects of this invention are achieved, and which is well adapted to meet the conditions of practical use.

5 As various possible embodiments might be made of the above invention, and as various changes might be made in the embodiment above set forth, it is to be understood that all matter herein set forth or shown in the accompanying drawing is 10 to be interpreted as illustrative and not in a limiting sense.

Having thus described my invention, I claim as new and desire to secure by Letters Patent:

A buckle for a shoe having a slit at the front extending to its upper edge forming a pair of opposed edges and a reinforcing strip embedded in each edge, said buckle comprising a channel shaped member to be fixed to one of said strips and having parallel walls formed with aligned notches, a channel shaped member to be fixed to the other reinforcing strip, a link pivoted to said last mentioned member, a lever pivoted to said link, said lever having a handle at one end, a pin 5 at the other end, said pin being adapted to be engaged within said notches to lock said buckle.

ABRAHAM I. LEVINE.
